(57) **CLAIM**

The ornamental design for a tablet computer, as shown and described.

DESCRIPTION

FIG. 1 is a perspective view of a tablet computer showing our new design;

FIG. 2 is a front view thereof;

FIG. 3 is a rear view thereof;

FIG. 4 is a left side view thereof where the right side view is a mirror image;

FIG. 5 is a top plan view thereof where the bottom plan view is a mirror image;

FIG. 6 is a rear perspective view thereof;

FIG. 7 is a perspective view thereof in which the subject design has been curved on its horizontal axis;

FIG. 8 is a front view of FIG. 7;

FIG. 9 is a rear view of FIG. 7;

FIG. 10 is a left side view of FIG. 7 where the right side view is a mirror image;

FIG. 11 is a top plan view of FIG. 7 where the bottom plan view is a mirror image;

FIG. 12 is a rear perspective view of FIG. 7;

FIG. 13 is a perspective view thereof in which the subject design has been curved on its vertical axis;

FIG. 14 is a front view of FIG. 13;

FIG. 15 is a rear view of FIG. 13;

FIG. 16 is a left side view of FIG. 13 where the right side view is a mirror image;

FIG. 17 is a top plan view of FIG. 13 where the bottom plan view is a mirror image; and,

FIG. 18 is a rear perspective view of FIG. 13.

The broken lines depict portions of the tablet computer that form no part of the claimed design.

1 Claim, 18 Drawing Sheets
